US00D968365S

(12) **United States Design Patent** (10) **Patent No.:** **US D968,365 S**
(45) **Date of Patent:** **** Nov. 1, 2022**

(54) **EAR DEFENDER**

- (71) Applicant: **JSP Limited**, Oxford (GB)
- (72) Inventors: **David Pratley**, Oxford (GB); **Tom Malloy**, Oxford (GB)
- (73) Assignee: **JSP Limited**, Oxfordshire (GB)
- (**) Term: **15 Years**
- (21) Appl. No.: **29/731,813**
- (22) Filed: **Apr. 17, 2020**

(30) **Foreign Application Priority Data**

- Oct. 18, 2019 (EP) 007061114-0005
- (51) **LOC (13) Cl.** **14-01**
- (52) **U.S. Cl.**
USPC **D14/206**; D14/226

(57) **CLAIM**

The ornamental design for an ear defender, as shown and described.

DESCRIPTION

FIG. 1 is an isometric perspective view of an ear defender, illustrating our new design;

FIG. 2 is a front view thereof;

FIG. 3 is a back view thereof;

FIG. 4 is a left view thereof;

FIG. 5 is a right view thereof;

FIG. 6 is a top view thereof; and,

FIG. 7 is a bottom view thereof.

The broken lines illustrate a portion of the ear defender that forms no part of the claimed design.

1 Claim, 7 Drawing Sheets
